METHOD OF AND APPARATUS FOR COATING
SHEET METAL CONTAINER SIDE SEAMS

Sylvester L. Flugge, Chicago, Ill., assignor to Continental Can Company, Inc., New York, N. Y., a corporation of New York

Application December 15, 1937, Serial No. 180,052

9 Claims. (Cl. 113—7)

The invention relates generally to the art of interiorly coating containers while they are in process of formation and primarily seeks to provide a novel method of and apparatus for applying a stripe of suitable protective coating material along the side seams interiorly of the containers as they are being fed along in the forming machine.

Many products, such as beer, wine, carbonated water, grape juice, and cranberry juice, cannot be packed in metal cans unless a protective lining is used that completely insulates the product from the metal of the can. The design of cans is generally such that the side seams are the most difficult portions of the cans to cover with protective coatings such as lacquer or enamel films. Thus, in the coating of can bodies by the well known methods of dipping, flushing, or spraying, several coating applications have been necessary in order to provide adequate protection at the side seams, resulting in great waste of coating materials as a result of the extra coatings not needed at the main body portions of the cans. Attempts to coat the can body blanks prior to the shaping thereof have been but partially successful since the seam portions necessarily are scraped and marred during the formation of the side seams. These difficulties have brought about the practice of precoating the body blanks except at the edges to be interlocked in the formation of the side seams and subsequently applying a protective stripe over the formed side seams, although the side seams may be coated prior to the application of overall interior coatings, if desired, so as to provide a double coating only at the seams.

Prior to the present invention, the side seam stripping was applied just after the can body side seams had been solder-bonded. In order to assure perfect alignment the stripping must be applied while the can bodies are oriented, or travelling along under position control, on the body maker. Just after leaving the solder-bonding station, however, the side seams are quite hot and difficulty has been experienced in applying the stripping over these hot surfaces.

In the present invention the side seam striping is applied after the side seams are formed and before the seams are solder-bonded, the heat at the solder-bonding station being utilized to heat-harden or bake the stripe coating. When the stripe coating is applied by means positioned in advance of the solder-bonding station, say for example on the stub horn, the heat of the soldering operation will drive off solvents and chemi-

cally convert a suitable striping material to an insoluble protective film. Since the material is applied to the seams before soldering, and at room temperature, the difficulties brought about by high and variable temperatures of the seam are eliminated from the step of actually applying the striping. Furthermore, the positioning of the side seams is definite and constant and no orienting difficulties are presented. A solvent having a high boiling point and which will give a good film deposition may be used since it will be driven off during the bake provided in the solder-bonding operation. This bake also is used to chemically convert the striping film. The heat at the solder-bonding station is thus used to evaporate solvents without resort to special ovens and also provides a high bake for special heat convertible films which could not otherwise be used, because a high bake after soldering would be detrimental to the soldered seams.

In its more detailed nature, therefore, the invention resides in the provision of a novel method of and apparatus for shaping can bodies and forming side seams longitudinally therein, moving the can bodies longitudinally while maintaining the seams in a common line, applying a stripe of protective coating material along the seams, and simultaneously solder-bonding the seams and heat-hardening said striping.

With these and other objects in view that will more fully appear, the nature of the invention will be more clearly understood by following the description, the appended claims, and the several views illustrated in the accompanying drawings.

In the drawings,

Figure 1 is a somewhat diagrammatic vertical longitudinal section illustrating the invention embodied in a can body forming apparatus.

Figure 2 is a left end view of the apparatus shown in Figure 1, parts being shown in vertical cross section.

Figure 3 is a vertical cross section taken on the line 3—3 on Figure 1.

Figure 4 is an enlarged fragmentary vertical longitudinal section of the horn at the stripe applying station.

Figure 5 is detail vertical cross section taken at the solder-bonding and stripe baking station.

Figures 6 and 7 are detail perspective views respectively illustrating can seam portions before and after stripe coating thereof.

Can body forming machines are well known and usually include a forming horn, means for feeding body blanks or sheets laterally or longitudinally to the horn, means for shaping the blanks

about the horn and for longitudinally seaming the bodies and bumping the seams, means for feeding the formed bodies along the horn, and means for solder-bonding the longitudinal body seams. All such devices are shown in detail in prior patents of which Troyer, 1,772,820, of August 12, 1930, is an example, and they, of themselves, form no part of the present invention except insofar as they form supporting elements in novel combinations hereinafter to be described.

In the practical development of the invention the body blanks may be fed to the forming devices in the manner shown in the Troyer patent or in any approved manner. The body shaping devices herein generally designated 5, the bumping means 6, and the oscillating arm 7 by which movement is transmitted to the formed body feeding means, may be constructed and operated generally as shown in the Troyer patent, and a seam bonding or soldering means 8 of the roll or any other approved type may be employed. Likewise, any suitable heating means generally designated 9 may be employed to produce the heat essential at the composite solder-bonding and stripe baking station.

Suitable reciprocating feed bars 10, to which motion is imparted by the arm 7, move the formed can bodies 11 step-by-step along the cylindrical horn 12. The horn 12 is grooved as at 13 to receive and guide the side seams until feed and guide control is taken over by the chain 14 which continues the feeding of the can bodies along and off the horn 12, into and through the outside horn. The outside horn comprises a pair of spaced members 15 having opposed half-cylindrical supporting surfaces 16 for receiving the travelling can bodies.

In advance or ahead of the solder-bonding station, the horn 12 has its under surface recessed as at 17 to receive a hollow casing 18 including a removable end wall 19 and adapted to be removably secured in the recess as indicated at 20. The casing is open along the bottom as at 21 to permit an applicator roll 22 to project therefrom in position for contacting can body seams along the full length thereof as shown in Figures 1 and 3 of the drawings. The roll 22 has trunnion bearings, as at 23, in the respective end walls of the casing.

The applicator roll 22 may take the form of a brush, or it may be provided with a soft absorbent sheath, and a perforated drip pipe 24 is mounted in the casing above the roll for the purpose of supplying coating material to said roll to be in turn deposited by the roll along the can body side seams. The coating material is supplied by a pipe line 25, removably secured as at 26 to the casing and extended through a bore provided therefor in the horn 12, from a suitable drip cup or reservoir 27. Rotation is imparted to the roll by a drive shaft 28 removably connected to one end of the roll, as at 29, and projected through the horn for connection with any suitable driving connection generally designated 30. See Figures 1, 2, 3 and 4.

Each infed blank is formed into a cylindrical can body and side seamed by the parts 5, 6 at the forming station. The can body thus formed is moved step-by-step along the horn to the striping station where the seam interiorly of the can body is striped with the coating material by the rotating roll 22. The conveyor 14 then feeds the striped can body off the horn 12 and into the outside horn 15, 16 to the solder-bonding and baking station. During the feeding of the can

bodies the horn groove 13 and the hook lugs on the feeding devices 10 and 14 maintain position control over the can bodies, assuring proper alignment of the side seams with the coating and soldering rolls. At the last mentioned station the side seam is solder-bonded and the protective coating material is suitably baked or heat-hardened, and after the conclusion of this step of the method the can bodies may be fed off into the receiving lines by a suitable feed off conveyor 31. 10

The can bodies may be thus seam striped before or after protective coatings are applied to the remaining surfaces of said bodies. In Figures 6 and 7 I have illustrated portions of a can body in which the blank had been coated, except for the edge portions in which the side seam was to be formed, prior to being fed into the body forming apparatus. The seam of the can body is indicated at 32, and the solder-bonding at 33. Body coating material is indicated at 34, being 20 terminated at 35, just short of the seam, leaving bare spaces 36. Bare spaces thus left, as well as the seam structure 32, are adequately coated by the protective stripe 37 applied as hereinbefore described.

It is to be understood that the specific apparatus elements herein disclosed are merely exemplary in nature and may be variously altered without departing from the spirit of either the method or the apparatus phase of the invention. 30 For example the applicator device may comprise a stationary drag, or may take the form of a brush or roll rotatable about a transverse instead of longitudinal axis. It is possible also to perform the seam bonding and stripe baking step 35 at a welding instead of a soldering station.

Two types of film forming striping material may be used: (1) a lacquer type which produces the finished film by evaporation of solvent alone without resort to oxidization or polymerization, and 40 (2) a heat reactive type which produces the finished film by evaporation of the solvents plus a chemical reaction of the film either by oxidization, polymerization, condensation or by combination reactions. One advantage of the reactive type is that it becomes insoluble in solvents to which it may be subjected during the application of further protective coatings of lacquer to the inside of the can body by spraying, dipping, flooding, or flushing methods.

The temperature of the side seam of a can body during soldering is high (450° to 600° F. or higher) but the time interval at this temperature is but a few seconds. The striping material must have the proper solvents in a minimum 55 quantity so that they can be driven from the film without causing bubbles, craters, and other undesirable film defects. Moreover, the film must withstand the high temperature without blistering or charring. Because the bake is short, heat 60 reactive materials must be designed to convert to an insoluble hard film in the very short interval available. Ordinary polymerizing or oxidizing finishes do not react or dry fast enough to be used for this striping. Ordinary driers, such 65 as lead, manganese, cobalt and iron driers used in paints, varnishes and enamels, will not increase sufficiently the rate of conversion to make it possible for the reaction to be complete before the seam cools. However, the conversion of a reactive type finish may be greatly accelerated by the decomposition of nitrocellulose which occurs when it is heated at temperatures such as are experienced during soldering. Thus, by the proper selection and proportioning of oil and resin, in 70 75

combination or alone, nitrocellulose and suitable solvents, many protective film forming combinations can be made which will bake satisfactorily during the short soldering operation. The nitrocellulose decomposition products so accelerate the conversion of the film to an insoluble protective film that the desired reaction is completed in the short time available.

5 Since the striping material is applied and baked 10 on the body maker and the application and baking is completed within a few seconds in a relatively small enclosed space, there is little or no danger of damaging either the striped film or the machine.

15 I claim:

1. In can body forming apparatus wherein is provided a horn, side seam forming means, seam soldering means, and means including the horn and feeding devices for guiding and feeding the 20 cans to the soldering means with the seams properly aligned; the combination with the guiding and feeding means and the soldering means, of means mounted directly in the horn in advance 25 of the soldering means for applying to the seams 30 interiorly of the can bodies a coating of protective material thereby utilizing the heat of the soldering operation to set the applied coating material.

2. In can body forming apparatus wherein is provided can body forming mechanism including 35 side seam forming means, and side seam soldering means; the combination with the soldering means of means disposed between the seam forming means and the seam soldering means for applying to the seams interiorly of the can bodies 40 a coating of protective material thereby utilizing the heat of the soldering operation to set the applied coating material.

3. In can body forming apparatus wherein is 45 provided can body forming mechanism including side seam forming means, and side seam soldering means; the combination with the soldering means of means disposed between the seam forming means and the seam soldering means for applying to the seams interiorly of the can bodies 50 a coating of protective material, and a horn along which the cans are guided to the soldering means, said coating material applying means being mounted directly in the horn.

55 4. In can body forming apparatus, side seam soldering means, means including a horn for guiding can bodies to the soldering means, means including an applicator roller mounted directly in the horn for applying to the seams interiorly of the can bodies a coating of protective material, means to feed coating material to said roller, and means to impart rotation to said roller.

60 5. In can body forming apparatus, side seam soldering means, means including a horn for guiding can bodies to the soldering means, means including an applicator roller mounted directly in the horn for applying to the seams interiorly of the can bodies a coating of protective material, means to feed coating material to said roller,

means to impart rotation to said roller, and means for feeding formed can bodies and for controlling the position of side seams thereof while passing through the coating material applying and the soldering means.

6. In side seamed can body forming apparatus, 10 means for applying to the seams interiorly of the can bodies a coating of protective material, means for solder-bonding the seams and simultaneously heat-hardening the applied coating material, and means for feeding can bodies past the coating applying means and the solder-bonding means with the side seams of said cans presented for engagement by each said means.

15 7. The method of forming can bodies and coating the seams thereof interiorly of the bodies which comprises, shaping the can bodies from blanks to which a protective coating has been applied over all surface areas to be presented inwardly of the can bodies except such areas as are to be formed into side seams and forming side seams longitudinally therein, applying a protective coating having the quality of becoming set by application of heat along the uncoated seam 20 portions interiorly of the bodies, and bonding the 25 seams by an operation in which the application of heat is inherent and utilizing said heat for heat-hardening said coating.

30 8. The method of forming can bodies and coating the seams thereof interiorly of the bodies which comprises, shaping the can bodies from blanks to which a protective coating has been applied over all surface areas to be presented inwardly of the can bodies except such areas as 35 are to be formed into side seams and forming side seams longitudinally therein, moving the can bodies longitudinally while maintaining the seams in a common line, applying a protective coating having the quality of becoming set by 40 application of heat along the uncoated seam portions interiorly of the bodies as they are moved along, and solder-bonding the seams and utilizing the heat incident to the solder bonding for 45 heat-hardening said coating as the can bodies are moved along.

50 9. The method of forming can bodies and coating the seams thereof interiorly of the bodies which comprises, shaping the can bodies from blanks to which a protective coating has been applied over all surface areas to be presented 55 inwardly of the can bodies except such areas as are to be formed into side seams and forming side seams longitudinally therein on the forming horn of a can body forming apparatus, applying a protective coating having the quality of becoming set by application of heat along the uncoated seam portions interiorly of the can bodies while they are on the relatively cool horn, moving the can bodies longitudinally while maintaining the seams in a common line, and solder-bonding the 60 seams and utilizing the heat incident to the soldering function to bake the applied protective coating.

SYLVESTER L. FLUGGE.
